UNITED STATES PATENT OFFICE.

JAMES BAIRD QUINN, OF ST. PAUL, MINNESOTA.

VALVE-GEAR.

SPECIFICATION forming part of Letters Patent No. 329,338, dated October 27, 1885.

Application filed August 7, 1885. Serial No. 173,830. (No model.)

To all whom it may concern:

Be it known that I, JAMES BAIRD QUINN, of St. Paul, in the county of Ramsey and State of Minnesota, have invented a new and Improved Valve-Gear for Steam-Engines, of which the following is a full, clear, and exact description.

The object of my invention is to provide a new and improved steam-engine, which is especially adapted for river-steamers propelled by a stern wheel turned by a high-pressure engine upon one side and low-pressure engine on the other.

The invention consists of two swinging arms deriving their motion from the wheel-shaft by suitable connections, of two arms which impart motion to the slide-valve and automatically cut off the steam by adjustable dogs placed on segments, and of a device for regulating the position of the dogs on the segments.

The invention consists of various parts and details, hereinafter more fully set forth and described.

Reference is to be had to the accompanying drawings, forming part of this specification, in which similar letters of reference indicate corresponding parts in all the figures.

Figure 1 is a vertical side elevation, partly in section, of my improvement. Fig. 2 is a plan view of the same, partly in section. Fig. 3 is a vertical cross-section on the lines $x-x$ of Fig. 1. Fig. 4 is a vertical cross-section on the line $y-y$ of Fig. 5. Fig. 5 is a bottom view of the cut-off mechanism.

The steam-cylinder A is provided on each end with the ports a and the steam-chests B B, in each of which is placed a sliding valve, C, actuated by means of the valve-rod D, from the valve-gear E, placed between the steam-chests B B, and supported above the center of the cylinder A. The balance-valve C is provided with a packing-ring, C', resting in a groove, C'', formed on the top of the valve and backed by a suitable elastic packing, C'', which is pressed against the ring C' by a follower, C', with a Δ -shaped upper surface and supported by springs, and the steam which enters the groove C', by suitable apertures in the bottom of the groove C'. The valve C is also provided with the exhaust-cavity C⁵, which connects with

the exhaust-chamber b by means of the exhaust-port b'.

Centrally between the steam-chests B B is mounted on suitable bearings the shaft F, which receives a rocking motion from the eccentric on the wheel-shaft by means of suitably-jointed rods attached to the crank F', keyed on the shaft F. On the shaft F are keyed the arms G, extending downward and in line with the crank F', and swinging loosely on the shaft F are the two link-arms H H, which are each connected to their respective valve-rods D by the links H' and the lugs H''. Each lug H'' is tapped and screws on the valve-rod D, and is secured on the same in any desired position by jam-nuts. The inner ends of the valve-rods D are supported in suitable keepers, D', bolted to the plate B', fastened to the steam-chests B B. Each driving-arm G is provided on its lower end with a notched piece, G', and each link-arm H is provided with a rod, I, placed in lugs cast on the outside of the arm H, and having a spring, I', which keeps the rod I in proper position, and allowing an upward motion of the rod I when disengaging the arm G. The lower end of the rod I forms into the right-angle arm I² turned inward, which is engaged by the notched piece G' on the arm G, when the latter is in a vertical position and passing the center. To each side of the plate B' is attached a segmental arm, J, on which is placed, and adjustable thereon, the tripping-dog K. The under side of the cross-plate B' is provided with grooves B'', in which slide the two racks L, held on the plate B' by suitable keepers, L'. Each rack is provided with a slotted arm, L'', in which extends a stud, K', secured to the lower end of the tripping-dog K. The racks L are moved in opposite directions at the same time by the pinion M, placed between the racks L on the plate B', and provided with a hand-wheel, M'. The pinion is locked in any position by the spring-latch M''. The valve-rod D projects beyond the outer end of the steam-chest B, and is provided on its extreme end with the enlargement D'', which has a bearing on the keeper N, held in place by the rods N', secured to steam-chests B. Keeper N is provided with the dash-pot O, of usual construction, vented and regulated by

stop-cocks in the ordinary way, and having the yoke O', which extends around the rods N' to receive the pressure of the spring N², placed on the said rods N', between the yoke 5 O' and the steam-chest B. It is obvious that when the valve-rod D moves in an inward direction it carries the dash-pot O with it and compresses the spring N², and when the valve-rod D is returning, the dash-pot O, under the 10 pressure of the spring N², moves with the piston-rod until seated in the keeper N, after which the valve-rod may move freely without any connection with the dash-pot O. The enlarged part D² of the valve-rod D is provided 15 with a square projection, D³, by which the valve-rod D may be turned and the slide valve C adjusted without removing the cover of the steam-chest B. The dash-pot is shown as placed entirely outside of the steam-chest 20 B; but it can be attached directly to the steam-chest B, and the rods and spring placed inside.

The operation is as follows: The rocking shaft F imparts a swinging motion to the arms G. The movement of both being alike, it is only necessary to describe the operation of one arm. The arm G on passing the center in the direction of the arrow a' engages with its notched piece G' the angular arm I' of the bolt I, placed on the arm H, and carries the latter 25 with it until the angular arm I' is released by striking the tripping-dog K, and returns to its former position by the pressure of the spring N² on the rods N'. This movement of the arm H causes the valve C to open the port 30 a and admit steam to the one end of the cylinder A, and cut off the steam according to the position of the dog K on the segment J. It will be seen that the dogs K are adjusted on the segment J by turning the hand-wheel 35 M', which causes a movement of the racks L in an opposite direction from each other, whereby the dogs K approach or recede from the ends of their segments. The dogs K are thus adjusted simultaneously for any desired points 40 of cut-off; or they may be run out to the extremities of the segments J and completely out of reach of the bolt I, in which case the steam would follow the piston through its full stroke, thereby acting as a simple slide-valve engine. 45 The position of the dogs K on the segments J permits a very nice adjustment of the point of cut-off without requiring an extraordinary degree of excellence in the construction of the several parts, which are simple and easy to construct, and can be readily repaired in case 50 of necessity with such skill and appliances as are ordinarily to be found in any steamboat. On the return motion of the arm G in the inverse direction of the arrow a', the arm H is 55 again engaged by the swinging arm G and carried with the same its entire stroke, whereby the valve C moves in the direction of the arrow d' and connects the ports a and b', and thereby exhausts the steam. It will be seen 60 that when the valve C travels in the direction of the arrow a' the valve-rod carries the dash-

70 pot O and yoke O' with it and compresses the springs N², and, returning, the dash-pot O under the pressure of the spring moves with valve-rod D until seated, after which the valve-rod D moves freely without any connection with the dash-pot O.

Having thus described my invention, what I claim as new, and desire to secure by Letters Patent, is—

75 1. In a steam-engine, the swinging arms G, deriving their motion by suitable connections from the wheel-shaft, in combination with the arms H, the segment J, the dogs K, the links H', the lugs H², the valve-rod D, the balanced slide-valve C, and the cylinder A, substantially as shown and described.

80 2. In a steam-engine, the swinging arm G, provided with the notched piece G', in combination with the arm H, the rod I, the link H', the lug H², the valve-rod D, and the balanced slide-valve C, substantially as shown and described.

85 3. In a steam-engine, the swinging arm G, provided with the notched piece G', in combination with the arm H, the rod I, the angular arm I', the spring I', the segment J, and the dog K, substantially as shown and described.

90 4. In a steam-engine, the swinging arm G, provided with the notched arm G', the arm H, the rod I, the angular arm I', the spring I', the segment J, and the dog K, in combination with the link H', the adjustable lug H², the valve-rod D, the slide-valve C, the keeper N, the springs N², the dash-pot O, and the yoke O', substantially as shown and described.

95 5. In a steam-engine, the arm G, the arm H, the segment J, the dog K, the valve-rod D, the slide-valve C, the keeper N, the rods N', the spring N², the dash-pot O, and the yoke O', in combination with the cylinder A, the inlet-port a, and the exhaust-port b', substantially as shown and described.

100 6. In a steam-engine, the segments J, the dogs K, and the studs K', in combination with the slotted keepers L², the racks L, and the pinion M, substantially as shown and described.

105 7. In a steam-engine, the arms G and H, the rod I, the angular arm I', and the spring I', in combination with the segments J, the dog K, the studs K', the keepers L², the racks L, the pinion M, and the hand-wheel M', substantially as shown and described.

110 8. In a steam-engine, the segments J, the dogs K, and the studs K', in combination with the slotted keepers L², the racks L, the keepers L', the pinion M, the hand-wheel M', and the spring-latch M², substantially as shown and described.
